(57) **CLAIM**

I claim the ornamental design for a set of front and rear panels for a shoulder pad assembly, as shown and described.

DESCRIPTION

FIG. 1 is a perspective view of a set of front and rear panels for a shoulder pad assembly according to the present design; FIG. 2 is a front elevational view of the set of front and rear panels for a shoulder pad assembly of FIG. 1;

FIG. 3 is a rear elevational view of the set of front and rear panels for a shoulder pad assembly of FIG. 1; and, FIG. 4 is a top plan view of the set of front and rear panels for a shoulder pad assembly of FIG. 1.

The broken lines in the Figures are for illustrative purposes only and form no part of the claimed design.
